UNITED STATES PATENT OFFICE.

HENRY VANGUNTEEN, OF HARRISBURG, PENNSYLVANIA.

DISINFECTION DEVICE.

Application filed June 26, 1926. Serial No. 118,683.

This invention relates broadly to disinfecting apparatus, but it more especially comprehends the type adaptable for use in connection with a mausoleum or crypts of a mausoleum.

An important object of this invention is to provide an improved means for deodorizing and purifying such vitiated air as may develop in a mausoleum or crypt or series of crypts contained therein.

The principal object of this invention is the provision of an apparatus of this character embodying a substantially V-shaped container having a tortuous air passage intercepting its lower end and discharging above the top thereof, said container adapted to be filled with a disinfecting material and a sealing material, the disinfecting material adapted to feed into the air passage so that the vitiated air as it passes therethrough will be deodorized and purified, the sealing material tending to force the disinfecting material into said passage and upon the latter's consumption automatically sealing said passage.

A still further object of this invention is to provide a container as above described with its lower end intersecting an air passage communicating with the crypt of a mausoleum, said container adapted to be filled with a disinfecting material and a sealing material, each successively feeding into said air passage, and means positioned in said air passage to limit the flow of said disinfecting material therein and to cooperate with said sealing material to effect the sealing of said air passage after the disinfecting material has been consumed.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a perspective view of my improved mausoleum disinfecting apparatus;

Fig. 2 is a vertical section of Fig. 1; and

Fig. 3 is a longitudinal sectional view of base member 5.

The devices of this general character with which I am familiar have proven unsatisfactory, in some instances owing to the fact that

the flow of the disinfecting materials by virtue of the construction of the apparatus and the use of sand or similar heavy substances frequently effected sealing of the air passage-way considerably in advance of the total consumption of the disinfecting material, thereby not only causing wastage of such material but greatly decreasing the efficiency of the device; and it was to overcome such deficiencies and to provide an apparatus simple in construction and so arranged that the material intended to ultimately effect automatic sealing of the air passage cannot reach such passage until the complete consumption of the disinfecting material has taken place, while at the same time insuring that even such disinfecting material that may adhere to the container walls will be advanced to the air passage ahead of the sealing material, that I designed the device forming the subject matter of this invention.

In the illustrated embodiment characterizing this invention, there is shown a substantially rectangular hollow base member 5 formed with an inlet opening 6 in one of its sidewalls slightly spaced from one end adapted to communicate with the interior of a mausoleum or crypt, and a similar opening 7 in the top of said member 5 at its opposite end adapted to receive the lower end of an exhaust conduit or flue member 8 which with member 5 forms in effect a continuous air passage from the said mausoleum or crypt to conduct the vitiated air from the mausoleum and discharge it in purified form, as will hereinafter more fully appear.

Suitably secured within the member 5 to the bottom and sidewalls but spaced from the top are the inclined baffle or hopper plates 9 forming in effect an auxiliary receptacle or hopper 10, the purpose of which will be hereinafter explained.

The top wall of member 5 is also formed with an opening 11 adapted to receive the lower end of a substantially V-shaped container 12 the sidewalls of which are adapted to extend within member 5, and into the hopper 10 below the upper edges of the plates 9 and transverse of said member 5, as clearly shown in Fig. 2 of the drawings.

Hingedly secured to the sidewalls of the container 12 as at 13 is a separator plate 14 adapted to initially separate the disinfecting crystals or other material 15 from the sealing material 16 of any suitable substance.

which if desired may be heavier than the material 15, for a purpose which will be more fully explained as the description proceeds.

In connection with the operation of the device, it will be noted that initially the container 12 is partially filled with a suitable disinfecting material such as disinfecting crystals or the like, the plate 14 being then lowered and the remainder of the container 10 filled with any suitable sealing material such as ground or pulverized glass or the like.

It is apparent that the hopper or receptacle 10 and the openings between the upper edges of the plates 9 and the lower edges of the container 12 are filled with the disinfecting material so that the vitiated air entering the opening 6 is forced to travel through said material thereby deodorizing and purifying the same prior to its discharge from the flue or vent 8.

The member 14 somewhat retards the downward force of the weight of the sealing material 16 until a portion of the disinfecting material 15 has been consumed, thereby preventing undue pressure on said disinfecting material and causing it to flow too rapidly out of said container.

The further advantage of placing the disinfecting and sealing materials in the same receptacle is that necessarily all of the disinfecting material must be consumed before the sealing material can reach the air passage and effect sealing thereof. In this connection it will be further noted that by forming the receptacle 10 and extending the lower end of container 12 therein, a tortuous air passage through the disinfecting material is effected so as to lengthen the air travel therethrough and at the same time limiting the amount of disinfectant within the pas-

sage, so that the greatest possible purification will be effected with a minimum consumption of the disinfecting material. Additionally, this construction insures a perfect sealing of the air passage by the sealing material when all of the disinfecting material has been consumed.

Although in practice I have found that the form of my invention illustrated in the accompanying drawings and referred to in the above description as the preferred embodiment is the most practical and efficient; yet realizing the conditions concurrent with the adoption of my device will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claim:

A disinfecting device comprising a container having an air passage communicating therewith, said passage being formed with inclined partitions spaced from the top thereof forming a receptacle or hopper, the lower end of said container projecting into said receptacle, a disinfecting material and a sealing material in superposed relation with respect to said disinfecting material adapted to fill said container and to successively feed into said receptacle to obstruct said passage and effect, respectively, purification of the vitiated air and the sealing of the said passage after the disinfecting material has been consumed.

HENRY VANGUNten.
